UNITED STATES PATENT OFFICE.

FRANZ TRINKS, OF BRUNSWICK, GERMANY.

CALCULATING MACHINE.

Application filed November 9, 1921 Serial No. 514,078.

To all whom it may concern:

Be it known that I, FRANZ TRINKS, residing at Brunswick, Germany, have invented certain new and useful Improvements in Calculating Machines, of which the following is a specification.

My invention relates to improvements in calculating machines, and more particularly in calculating machines of the type in which 10 a setting mechanism cooperates with two registering mechanisms, and in which in addition a revolutions counting mechanism is provided. By means of machines of this type multiplications can be performed in 15 which the number of the figures of the result exceeds that of the numeral wheels of each registering mechanism. The object of the improvements is to provide a machine of this class in which at the end of the calculation the multiplier is correctly displayed by the revolutions counting mechanism. With this and other objects in view my invention consists in the matters to be described hereinafter and particularly pointed 20 out in the appended claims.

For the purpose of explaining the invention an example embodying the same has been shown in the accompanying drawing, in which the same letters of reference have 25 been used in all the views to indicate corresponding parts. In said drawing,

Fig. 1, is a front view of a part of the calculating machine,

Fig. 2, is a vertical cross-section taken on the line 2—2 of Fig. 1 showing the main revolutions counting mechanism and subsidiary revolutions counting mechanism forming a part of the main revolutions counting mechanism, and

Fig. 3 is a sectional elevation of the calculating machine showing the setting mechanism, the registering mechanisms, and the main and subsidiary revolutions counting mechanism.

In order that my invention be clearly understood I shall at first describe the method now in use for performing a multiplication in which the number of the figures of the product exceeds that of the numeral wheels 45 of each registering mechanism, reference being made to a calculating machine of the construction shown and described in the patent of the United States No. 705,838 to Hamann, granted July 29, 1902. A machine of this construction has been shown in Fig. 3 of the accompanying drawings, and

in addition the parts forming the subject matter of my invention have been shown as embodied in the said machine.

Referring at first to the old parts of the said calculating machine, the setting mechanism *p* consists of a rotary shaft *8* carrying setting wheels *1* each containing nine teeth 2 any number of which may be shifted outwardly by cam disks *3* provided one for each wheel. The setting wheels are adapted to be rotated from a machine crank *6* through the intermediary of gears *4* and *5*. In front of the setting mechanism there is a registering mechanism *q* adapted to be operated by the setting mechanism through the intermediary of a gear wheel *7*, as is known in the art. Below the registering mechanism *q* there is a second registering mechanism *r* adapted to be coupled with the registering mechanism *q* by intermediate gear wheels *8* provided one for each of the numeral wheels of the registering mechanisms *q* and *r*. The gear wheels *8* are rotatably mounted on a shaft *s* supported on arms *r* having rocking supports on the shaft *r* carrying the numeral wheels of the registering mechanism *r*, and they are adapted to be thrown into or out of engagement with the gear wheels of the registering mechanism *q* by rocking the arms *r* and the shaft *s* mounted thereon by means of a bell crank lever *t*. Both registering mechanisms *q* and *r* are mounted on a carriage *o* adapted to be shifted relatively to the setting mechanism *p* in a direction 90 parallel to the axis thereof.

Above the setting mechanism there is a revolutions counting mechanism *d* the numeral wheels of which are connected each with a gear wheel *i*. The revolutions counting mechanism *d* is adapted to be rotated from the machine crank *6* through the intermediary of a gear wheel *5* engaging in a gear wheel *11* keyed to a shaft *12*. On the said shaft a single tooth wheel *13* is longitudinally shiftable, which is connected with the carriage *o* by an arm *14*. Upon each revolution of the machine crank *6* the single tooth wheel advances one of the gear wheels *15* and the gear wheel *i* meshing therewith a distance corresponding to one value.

The parts so far described are known in the art. In order to perform a multiplication the intermediate gear wheels *s* are rocked into engagement with the gear wheels of the registering mechanism *q*, and the multiplication is carried out by means

- of the setting mechanism p and both registering mechanisms q and r , until the capacity of the registering mechanisms is exhausted, which is indicated by a bell or the like.
- 5 In the course of this calculation the carriage o is successively shifted to the right according to the number of the figures of the multiplier. Now the carriage o is returned into initial position, so that the intermediate gear wheel 7 located at the right of the set of intermediate gear wheels is in position for cooperation with the first setting wheel 1. The intermediate gear wheels s are rocked out of engagement with the gear wheels of the registering mechanism q , the registering mechanism q is reset, and from the figures displayed by the registering mechanism r those located at the left of the single tooth wheel, before the carriage o was shifted, are carried over to the right hand numeral wheels of the registering mechanism q , which is done for example by hand after opening the top plate of the machine, or which may be done by setting the said number on the setting mechanism p and once operating the machine crank 6. Now the multiplication is completed by means of the multiplicand set in the setting mechanism and the remaining figures of the multiplier, and the partial result thus obtained in the registering mechanism q is added to the partial result of the first calculation which is still displayed by the registering mechanism q .
- 35 Example: By means of a calculating machine having two registering mechanisms q and r each comprising ten numeral wheels the multiplication
- 40 $3232323 \times 292222 = 718293281706$
- 45 is to be performed.
- The number 3232323 is first set on the setting mechanism and multiplied four times by 2 while successively shifting the carriage o carrying the registering mechanisms q and r . Thereby the number 7182221706 is transmitted to the registering mechanism. Now the carriage o is shifted to the left and into initial position, the frame r^2 is rocked 50 downwardly with the gear wheels s out of engagement with the gear wheels of the registering mechanism q and the registering mechanism q is reset. As the carriage has been shifted to the fourth place and back 55 again the last four figures of the partial result have been determined. Accordingly the remaining figures 718222 are now transmitted to the second registering mechanism, whereupon the carriage carrying the registering mechanisms is again set in operative 60 position and the calculation is continued in the usual way by multiplying the number 3232323 by 22. Now the second registering mechanism displays the number 71829328 which is combined with the number 1706

left on the first registering mechanism into the final result 718,293,281,706.

When thus performing the calculation the revolutions counting mechanism does not display the correct multiplier 222222 but the number 2244. The object of the improvements is to avoid this error. For this reason I provide an indicating mechanism or subsidiary revolutions counting mechanism cooperating with the main revolutions counting mechanism and taking part in the movement thereof, which indicating mechanism is adapted to be rocked out of operative position at the end of the first partial calculation for preserving the partial multiplier (2222), so that after resetting the main revolutions counting mechanism the second part (22) of the multiplier can be displayed thereby. The true multiplier is obtained by combining both partial multipliers (2222: 22 = 222222).

In the example shown in the figures the indicating mechanism consists of a set of gear wheels a and numeral wheels b connected therewith, said wheels being loosely mounted on a shaft h secured to rock arms c . The numeral wheels b are adapted to be rotated from the gear wheels i of the revolutions counting mechanism d through the intermediary of gear wheels e , and they are adapted to be thrown out of operation by rocking the rock arms c and the indicating mechanism mounted thereon away from the gear wheels e . To the rock arms c noses m are secured which are adapted to engage in either one of a pair of notches g provided one in each of spring pressed locking pawls f for securing the indicating mechanism in operative and inoperative positions. The revolutions counting mechanism d and the indicating mechanism b are equipped with resetting means of any known or preferred construction represented in Fig. 1 by wing nuts k and l .

In the preferred construction shown in Fig. 1 the figures the resetting mechanism k of the main revolutions counting mechanism d is equipped with a cam n cooperating with the subsidiary revolutions counting mechanism b through suitable gearing for rocking the same into inoperative position when resetting the main revolutions counting mechanism. The subsidiary revolutions counting mechanism is rocked into operative position by hand, for example by depressing the rock arms c by means of the wing nuts l .

The revolutions counting mechanism and the indicating mechanism are used as follows: When performing the first partial multiplication both mechanisms are in operative positions, the revolutions counting mechanism d being rotated from the machine crank 6 and transmitting such rotation to the indicating mechanism b through

the intermediary of the gears *e*. At the end of the partial multiplication both mechanisms show the number 2222. Now the revolutions counting mechanism, *d* is reset, and the indicating mechanism *b* is rocked by the cam *n* out of engagement with the intermediate gear wheels *e*, whereupon the second partial multiplication is performed by which the number 22 is transmitted to the revolutions counting mechanism *d*. Finally the parts of the multiplier are combined (22, 2222=222222). Before starting a new calculation both mechanisms are reset.

15 I claim:

1. In a calculating machine, the combination, with the setting mechanism, and two registering mechanisms movable relatively to the setting mechanism, of main revolutions counting mechanism, and subsidiary revolutions counting mechanism adapted to be thrown out of relation for operation by the setting mechanism.
2. In a calculating machine, the combination, with the setting mechanism, and two registering mechanisms movable relatively to the setting mechanism, of main revolutions counting mechanism, and subsidiary revolutions counting mechanism adapted to be set into and out of cooperation with said main registering mechanism.

3. In a calculating machine, the combination, with the setting mechanism, and two registering mechanisms movable relatively to the setting mechanism, of main revolutions counting mechanism, subsidiary revolutions counting mechanism adapted to be set into and out of cooperation with said main revolutions counting mechanism, and means to lock said subsidiary revolutions counting mechanism in operative and inoperative positions.

4. In a calculating machine, the combination, with the setting mechanism, and two registering mechanisms movable relatively to the setting mechanism, of main revolutions counting mechanism, resetting means therefor, subsidiary revolutions counting mechanism adapted to be set into and out of cooperation with said main revolutions mechanism, and means intermediate said resetting means and subsidiary revolutions counting mechanism adapted when operating the resetting mechanism to set said subsidiary mechanism in inoperative position.

In testimony whereof I have affixed my signature in presence of two witnesses.
